United States Patent

Des. 235,889
Patented July 15, 1975

235,889

COIN VAULT

Ira J. Alligood, 1118 Roosevelt Ave.,
York, Pa. 17403

Filed July 26, 1973, Ser. No. 382,675

Term of patent 14 years

Int. Cl. D20—01

U.S. Cl. D31—23

Fig. 1

Fig. 2

Fig. 3

Fig. 4

Fig. 5

Fig. 6

FIG. 1 is a top plan view of a coin vault, showing one embodiment of my design.

FIG. 2 is a front elevation thereof.

FIG. 3 is a side elevation thereof.

FIG. 4 is a top plan view of a coin vault, showing another embodiment of my design.

FIG. 5 is a front elevation thereof.

FIG. 6 is a side elevation thereof.

The undisclosed sides of both embodiments of the coin vault shown in the preceding figures are mere images of the sides shown.

I claim:

The ornamental design for a coin vault, substantially as shown and described.
